UNITED STATES PATENT OFFICE.

GUSTAVUS S. PERKINS, OF HARTFORD, CONNECTICUT.

PNEUMATIC DOOR-CHECK.

SPECIFICATION forming part of Letters Patent No. 360,042, dated March 29, 1887.

Application filed August 2, 1886. Serial No. 209,714. (No model.)

To all whom it may concern:

Be it known that I, GUSTAVUS S. PERKINS, of Hartford, in the county of Hartford and State of Connecticut, have invented a certain 5 new and useful Improvement in Pneumatic Door-Checks, of which the following is a full, clear, and exact description, whereby a person skilled in the art can make and use the same.

My improvement relates to that class of 10 door-checks in which the elasticity of air when confined in a chamber is made use of as a buffer or cushion to prevent the slamming of a door in closing under the impulse of a spring.

15 The object of my improvement is mainly to provide a device of this class with a peculiar valve or vent that automatically regulates and controls the movement of the air out of and into the chamber in a cylinder in front of the 20 piston.

To this end my improvement consists in a cylinder having practically air-tight head in combination with a piston that bears the automatic self-regulating valve; and it further 25 consists in the combination of a cylinder with contained piston, and the peculiar levers that connect a door and its frame to such parts, as more particularly hereinafter described, and pointed out in the claims.

30 Referring to the drawings, Figure 1 is a front view of one form of my improved device as adjusted in position for use. Fig. 2 is a view in horizontal section through the door-check on the plane denoted by the line $x-x$ of Fig. 1.

35 Fig. 3 is a detail view in section on the same plane, showing the parts extended by the opening of the door. Fig. 4 is a detail front view of the piston. Fig. 5 is a detail rear view of the piston. Fig. 6 is a detail view in cross- 40 section through the piston and valve on plane denoted by line $y-y$ in Fig. 4. Fig. 7 is a detail view of the front end of a modified form of piston and valves. Fig. 8 is a detail view in cross-section through the latter form of piston and valves, showing comparative views 45 illustrating the operation of the valves.

In the accompanying drawings, the letter a denotes a door-frame; b , a door, and c the cylinder of the door-check. This cylinder is preferably 50 a metallic tube having firmly screwed or fastened to one end the back head, d , which is pivotally connected to a stand, e , the latter having the foot e' , through which screws are driven to fasten the stand to the jamb of the

door or to the door. In the drawings the cylinder is pivotally connected at the back head 55 to the door-jamb.

The letter f denotes the front head of the cylinder, that is firmly secured thereto, as by means of a screw-thread, and through the center of this front head passes the piston-rod g' , on the inner end of which is screwed the piston g . Within the cylinder, and between the back of the piston and the front head, is arranged a spiral spring, h , seated with one end 60 pressing against the piston and the other against the follower h' , that is seated on the ends of screws that are borne in threaded sockets in the front head, and preferably extend through it, so that their outer ends are accessible for the 65 purpose of adjusting the position of this follower with relation to the front head, so as to increase or decrease the tension of the spring h without removing the head from the cylinder. The outer end of this piston-rod g' is pivotally 70 connected to the lever k , that is a bent lever pivotally connected at its angle to the stand l , and at its other end to the tie-rod m . In the form shown this tie rod is pivoted to the guide-rod n , and to the connecting-arm o by a common pivot at the meeting point of these parts, the guide-rod being pivoted to lugs l' on a stand, l , at a point between the points of connection of the stand l and bent lever k and the bent lever and tie rod m , these three points 85 being about in line with each other when the parts are in their normal position, as seen in Fig. 1.

The connecting-arm o is pivoted to the bracket p , that is secured to the door b , and 90 when the latter is opened the arm pushes the tie-rod at its outer end, which in turn pulls on and rocks the bent lever, and thus draws the piston forward in the cylinder, compressing the closing spring, whether the latter is 95 enclosed in the cylinder or is attached to the door at some other point.

By means of the bent lever, the guide-rod n , and tie-rod m the travel of the piston in a given size of cylinder is reduced to a minimum. 100 (An examination of the position of guide-rod n and tie-rod m in Fig. 3 will show this.) The force of the compressed spring when the door is opened is thus used to the best advantage, and the door is prevented from traveling faster 105 in closing than the piston travels in the cylinder, and it also more effectually prevents the door from slamming than when the piston-

rod is pivoted directly to the tie-rod. It has been found by experiment and somewhat extended use of this device that the force required to first move the door in opening increases to about twice that amount until the door reaches an angle of sixty degrees and then the force decreases, but not to a degree to prevent the spring from starting the door very forcibly in closing.

10 At no time in the movement of the several levers and connecting parts does the pull of the spring upon the piston-rod lie in a line through the pivots or "over the center," as is the case in several prior devices, and thus 15 there is no pause in the closing movement of the door. The decreased play of the piston enables the cylinder to be made much shorter and cheaper than in prior devices having a spring of the same power and a cylinder of 20 the same diameter.

The follower h' , that is arranged between one end of the spring and the front head of the cylinder, is supported, preferably, on screws h^2 , that are adjustable in sockets in the follower, 25 and have shoulders bearing against the inner side of the front head, f . The tension of the spring may be easily controlled by this device. There is no provision made for the passage of air into or out of the cylinder c . In fact, the 30 latter is substantially air-tight; but the piston g is provided with a valve, q , that provides for the passage of air from one side to the other of the piston as it moves forward and back in the cylinder. This valve q has a broadened 35 head, q' , lying on the front side of the piston, and held with its stem q'' within the chamber r by the pressure of the spring r' . Within the chamber r , that is open through to the back of the piston, is seated a spiral spring, r'' , 40 with one end thrusting against a shoulder or lug within the chamber and the other against the valve, so as to hold it in its normal condition between the two springs and slightly raised from its seat. In this condition, when 45 the door to which this device is connected is opened, the piston moves toward the front head of the cylinder, the air passing quite freely through the valve in the piston, and offering practically no resistance to such forward movement of the piston. As soon as 50 the return movement of the piston is begun, as under the impulse of a spring, any quick movement of the piston causes the valve q to close upon its seat and prevent the passage 55 of air from the front to the back side of the piston.

The valve-seat is preferably provided with a relief-opening, S^2 , which consists of a very small channel in the face of the valve or seat, that allows a sufficient quantity of air to leak through to relieve the pressure on the back of the valve, due to the compression of the air in front of the piston, and as soon as this pressure of the compressed air is less than the pressure of the spiral spring in the chamber the valve opens and allows the air to pass more freely through it to the other side of the pis-

ton, which then continues its movement, and the door closes quietly.

Instead of providing the valve q or its seat with the relief-opening described, I may use a separate relief-valve, s , located at another point in the piston, and this may consist of a valve-seat formed on the back of the piston, into which the valve s is seated under the pressure of the spring s' . The office of the relief-valve is the same as that of the relief-opening. In order to provide for the tight packing of the piston, I use a cup-packing, t , of suitable material, as leather, secured to the piston by a disk-shaped clamp that is screwed upon an extension of the piston-rod, that is perforated for the free passage of the air.

The piston may obviously be packed in any other convenient way and the clamp secured by other means than screwing it onto the extension of the piston-rod; but the latter is preferable.

I claim as my invention—

1. In a door-check of the within-described class, the combination of the cylinder with pivot-bearings on its back head, the cylinder-supporting stand e , the piston and connected piston-rod, the bent lever and its supporting-stand, with one end of said lever pivotally connected to the piston-rod and the other to a tie-rod, the guide-rod n , and connecting-arm with its supporting-stand, the tie-rod, guide-rod, and connecting-arm being united by a common pivot, all substantially as described. 100

2. In a door-check of the within-described class, in combination with the cylinder and its connected piston and rod, a bent lever pivotally attached to the frame or casing of a door, to which part the cylinder is also connected, and having its outer ends pivotally connected to the piston and a tie-rod, respectively, and a guide-rod, also pivoted to a stand, all substantially as described, and for the purpose set forth. 110

3. In a pneumatic door-check, in combination, a cylinder with closed end, and a piston movable within the cylinder, with its outer edge having an air-tight packing, and the balanced valve borne by said piston to permit the passage of air through the piston, all substantially as described. 115

4. In a pneumatic door-check, a cylinder, c , and a piston, g , bearing the valve q , having a relief-opening, all substantially as described. 120

5. In a pneumatic door-check, in combination, a cylinder, c , and a piston, g , having the valve q balanced between the springs r and r'' , and having a relief-opening, all substantially as described. 125

6. In a pneumatic door-check, in combination, a cylinder, c , and a piston, g , having the balanced valve q , and a relief-valve, s , all substantially as described.

GUSTAVUS S. PERKINS.
